DUAL STEREOSCOPIC PROJECTOR

Filed Dec. 5, 1949

UNITED STATES PATENT OFFICE

2,598,573

DUAL STEREOSCOPIC PROJECTOR

Harold R. Lutes, Alhambra, Calif.

Application December 5, 1949, Serial No. 131,142

1 Claim. (Cl. 88—26)

1

This invention relates to projectors, and more particularly to a projector adapted to project a plurality of images to a screen in which means is provided for orienting one of said images with respect to the other, both vertically and horizontally.

Projectors of this type are useful in optometry, and it is one object of this invention to provide a projector which can be used by optometrists in the testing of the eyes of their patients for all of the ordinary factors to be considered in the fitting of glasses and for the purpose of correcting visual anomalies by visual training procedures.

It is a feature of this invention that two projector tubes are provided, each of which is provided with the conventional lenses forming the optical system of the tube, and adapted to project an image to a screen. Each of the tubes is separately mounted for rotation in a vertical plane, and for movement towards and away from each other in a generally horizontal plane.

It is accordingly one object of this invention to provide such a binocular projector in which each of the separate projecting tubes can be simultaneously moved towards or away from the other, or may be rotated with the other about a horizontally disposed axis.

It is another object of this invention to provide a device of the type described which is simple, sturdy, and economical of manufacture.

It is a further object of this invention to provide a device of the type described which is simple and easy to operate.

These and other objects and advantages of the invention will be apparent from the annexed specification, in which:

Figure 1 is a side view, partly in vertical section, of a projector embodying the present invention;

Figure 2 is a fragmentary plan view of the device shown in Figure 1, with the cover broken away for clarity of illustration;

Figure 3 is a front view, partly in section, of the device shown in Figure 1;

Figure 4 is an enlarged section taken along the line 4—4 of Figure 2;

Figure 5 is a perspective elevation of the tube mounting plate; and

Figure 6 is an enlarged section taken along the line 6—6 of Figure 2.

Referring now more particularly to the drawings, the invention is shown as including a base 10 having four downwardly extending legs 11, and having an opening 12 in the top thereof

2

generally rectangular in form. A casing 13 is provided having an L-shaped extension 14 running across the front of the casing and extending downwardly into the opening 12. The base 10 has a rearwardly extending flange 15 across the front thereof which is provided in the middle thereof with a thumbscrew 16, the lower end of which is adapted to engage the lower arm of the L-shaped extension 14, as clearly shown in Figure 1. The base 10 is likewise provided with a platform or shelf 17, upon which is suitably mounted a coil spring 18, one end of which engages the shelf 17, and the upper end of which engages under the lower arm of the extension 14.

15 The casing 13 is provided on either side thereof with a depending lug 19 which is bored as at 20 to receive the inner end of studs or pins 21, thus pivotally mounting the casing 13 on the base 10. From the foregoing description it will be apparent that the casing 13 and all of the mechanism carried thereby can be pivoted about the pins 21 by making up or backing off the thumbscrew 16, thus vertically adjusting the position of the image projected as hereinafter described.

20 The casing 13 comprises a base plate 22 and a cover 23. The cover 23 may be removed by disengaging the thumbscrews 24 from the lugs 25 formed integrally with the base plate 22. Within the casing 13 there is disposed a pair of tubes 26 formed in the conventional way to house projecting lights 27. The tubes are apertured as at 28 in alignment with reflecting mirrors 29, and again apertured at 30 to permit concentrated light to project from the tube. The base plate 22 is provided with a plurality of openings 31, 32, and 33 for ventilation, and a number of longitudinally extending slots 34 is provided in the cover 23 for the same purpose. The forward wall 35 30 of the casing is provided with a pair of openings 36, and aligned with the openings 36 are a pair of light-condensing optical systems conventional in form and indicated generally by the numeral 37. The light-condensing systems 37 can be attached to the forward wall 35 by the screws 38.

35 The outward side of the forward wall 35 is provided with a pair of spaced extensions or ribs 39 forming a channel 40. A plate 41 is provided adapted to be attached to the ribs 39 by the screws 42 (see Figure 4), and the plate 41 is provided with a centrally disposed, outwardly extending post 43 provided with male threads to receive a retaining nut 44. A tube mounting plate 45 is provided (see Figure 5), and is adapted to be pivotally retained upon the post 43 by

means of the nut 44. The plate 45 is provided with a channel 46 on the rear thereof having dimensions such that the plate 41 extends therein and permits limited pivoting of the plate 45 about the post 43. The plate 45 is provided with a pair of outwardly extending ribs 47 and 48, the rib 47 having an upwardly and inwardly beveled lower edge 50, and the rib 48 having a downwardly and inwardly beveled upper edge 49, thus forming a channel.

The forward wall 35 is provided with a forwardly extending lug 51 which is tapped to receive a thumbscrew 52, the lower end of which is adapted to abut the upper surface of the rib 47 adjacent one end thereof, as shown in Figure 3. The forward wall 35 is likewise provided with a similar lug 53 which is tapped to receive the threaded portion 54 of the cylinder 55. The cylinder 55 houses a coil spring 56 and a piston 57 having its lower end rounded as shown in Figure 6. The lower end of the piston 57 thus engages the upper surface of the rib 47 adjacent the end thereof opposite that engaged by the thumbscrew 52, and resiliently biases the plate 45 in a clockwise direction (Figure 3). A pair of projecting tubes 58 and 59, each containing the conventional optical pieces for projecting an image to a screen, are provided. The tubes 58 and 59 have bases 60, the rear ends of which are provided with an extension 61, the walls of which are beveled as at 62 and 63 to be received within the channel formed by the walls 49 and 50 of the ribs 47 and 48 for sliding engagement therein.

The plate 45 is provided with a pair of light openings 64 and 65, and the main wall of the plate 45 may be cut out as at 66 and 67 to reduce the bearing area against which the extensions 61 bear. The post 43 is internally threaded as at 68 to receive a stud 69. The stud 69 pivotally mounts a lever 70. The bases 60 of the projecting tubes 58 and 59 are each provided with an inwardly extending lug indicated at 71 and 72. The lugs 71 and 72 are adapted to receive the threaded portion of studs 73 and 74, respectively. The lever 70 adjacent the lugs 71 and 72 is provided with elongated slots 75 and 76 adapted to receive the shaft of the studs 73 and 74 which are prevented from escaping from the slots 75 and 76 by the enlarged heads thereof. The lever 70 is provided with an upwardly extending handle 77.

As the bases 60 of the projecting tubes 58 and 59 are slidably mounted within the plate 45 as hereinbefore described, it will be apparent that the projecting tubes can be moved toward or away from each other by moving the lever 70 by means of the handle 77 in either a counterclockwise or a clockwise direction, the studs 73 and 74 sliding in the slots 75 and 76 during this operation.

As the piston 57 resiliently engages one side of the rib 47 of the plate 45, and as the lower end of the thumbscrew 52 engages the other side thereof, it will be apparent that by backing off or making up the thumbscrew 52, the plate 45, and hence the projecting tubes 58 and 59 carried thereby, can be rotated about the axis formed by the post 43. The displacement of the projecting tubes 58 and 59 either horizontally or vertically as just described will be accompanied with a corresponding displacement of the optical images projected, as will be well understood by those skilled in the art.

The channel 40 is provided between the ribs 39 in order to receive a slide which may be provided with any pair of images which it is desired to project upon the screen, and by means of the controls just described, these images can be separated either in a horizontal or a vertical direction by the simple manipulation of the lever handle 77 or the thumbscrew 52.

A printed scale 100 for indicating the binocular distance may be provided having one end affixed to one of the bases 60, as at 101, and having its other end riding over the other base.

While there has been described what at present is considered a preferred embodiment of the present invention, it will be apparent to those skilled in the art that various changes and modifications can be made therein without departing from the essence of the invention, and it is intended to cover herein all such changes and modifications as come within the true spirit and scope of the appended claim.

I claim:

An optical image projector comprising: a housing; a pair of light sources in said housing; 25 a pair of image projecting optical systems mounted on said housing in operative alignment with said light sources and having parallel axes; first means mounting said projecting systems for movement towards and away from each other in 30 a generally horizontal plane; means mounting said optical systems for rotation about an axis intermediate of and parallel to the system axes; means defining a passage between said light sources and said systems adapted to receive an 35 image transparency, said first means comprising a channeled mounting plate and bases on said systems extending into the channel for sliding movement therein and a lever pivotally mounted between said bases; and pins carried by said 40 bases and extending into slots formed in said lever on opposite sides of its pivot whereby said bases are adapted for concurrent movement, said second means comprising a pivot supporting said mounting plate on said casing intermediate said 45 systems, resilient means biasing said mounting plate in one direction of rotation and screw means adjustably limiting and resisting said rotation.

HAROLD R. LUTES.
